EDISON A. FOUNDS, OF PHILADELPHIA, PENNSYLVANIA, ASSIGNOR OF ONE-FOURTH
TO ROBERT B. GRIMES, OF PHILADELPHIA, PENNSYLVANIA.

AEROPLANE KITE.

Application filed October 18, 1926. Serial No. 142,400.

This invention relates to kites and more particularly to new, interesting and educational improvements in aeroplane kites of the tractor biplane variety.

5 The principal object of the invention is to provide a kite in the form of a tractor biplane, comprising a plurality of miniature sections of conventional design, which are constructed in a manner adapted for the 10 rapid assembling and dismantling of the kite without the use of nails, pins or screw bolts for joining the various sections together, without the use of a single tool and which is also provided with flexible means 15 for staggering the upper front wing surface ahead of the lower wing surface for positioning the main wing surfaces at a true angle of incidence relative to the fuselage body therefor.

20 A further object of the invention is to provide an aeroplane kite of conventional miniature design, which is particularly adapted to be readily assembled or dismantled in a minimum period of time, without 25 the use of tools or other auxiliary equipment, one which will ride in the wind on an even horizontal heel, and one which is provided with a novel bridle cord for controlling the kite and automatically maintaining the same 30 in a true flight position at all times.

35 A further object of the invention is to provide an aeroplane kite as specified which will simulate the true flight of a full size aeroplane of approved type, and in addition thereto give the familiar whirring sound by means of a propeller having apertures therein and rotatably pivoted intermediate the end of the main wing spread in front thereof, in the well-known manner.

40 A still further object of the invention is to provide a toy aeroplane kite, as specified, which is cheap to manufacture, comprising a minimum of parts, adapted to be dismantled, compactly folded, and carried about 45 in a convenient manner, and which provides a subject for entertainment as well as the study of sustained flight principles involved in the heavier than air flying machine.

50 Other objects of the invention will appear in the following detail description, and in the accompanying sheets of drawing, wherein:

Figure 1 is a perspective view of the

aeroplane kite in assembled flight position with the bridle control cord therefor shown 55 in normal operating position.

Fig. 2 is a side elevation in longitudinal cross section thru the assembled frame members, illustrating the manner of forming and connecting the main wing surface with the 60 fuselage, the horizontal elevator surface to the rear end of the fuselage and the manner of pivoting the rudder in a vertical manner on the horizontal rudder.

Fig. 3 is a fragmentary top plan view of 65 the vertical and horizontal rear supporting and directing surface.

Fig. 4 is an enlarged fragmentary detail view of one of the mortised joints for receiving one of the fuselage forming tenons. 70

Fig. 5 is a similar view of the rear mortised joints for receiving the rear fuselage tenons.

Referring more particularly to the drawings, the aeroplane kite, hereinafter described, is a true miniature representation of the well-known tractor biplane type and is indicated for general reference by the reference character 10.

The aeroplane kite, 10, comprises a main upper and lower wing supporting surface, 11 and 12, which are each made up of two parallel sticks, 13, with a covering of paper or fabric thereon and extended therebetween. Intermediate the ends of the sticks, 13, a mortised block, 14, is provided and secured on the upper surface of each of the sticks, 13, to form a rectangular aperture, 15, for slidably receiving the ends of the fuselage forming members hereinafter described.

The front side surface of the upper and lower stick, 13, is provided with a retaining clip 16, of U configuration and secured centrally over the rectangular aperture, 15, in each of said sticks, 13, to provide an abutting member for the front ends, 17, of the fuselage sticks, 18 and 19, which are adapted to fit in the said apertures, 15, and also to provide a vertically disposed rectangular recess extended centrally and forwardly of the said sticks, 13, for receiving the ends, 20, of the front vertical wing spacing strut 21, which is likewise provided with rectangular apertures, 22, for alignment with the apertures, 15, to jointly receive the front

ends, 17, of the fuselage forming sticks, 18 and 19.

A second vertical spacing strut, 23, with its ends likewise provided with a rectangular aperture, 24, is oppositely disposed to the rear of the front strut, 21, for supporting the rear edge of the upper and lower wings, 11, and 12, with the rectangular aperture 24, in alignment with a similar aperture 15, in the rear sticks, 13, for passage therethru of the front portion of the fuselage forming sticks 18 and 19, in superposed parallel relation, as clearly shown in Fig. 1 of the drawing.

15 The rearwardly extending end portions of the fuselage forming sticks, 18 and 19, are then bowed in a tapering manner with the rear ends 25, thereof, joined together for passage thru a pair of parallel and oppositely disposed rectangular apertures, 26, which are provided on the upper surface of the sticks, 27, forming the horizontal rudder, 28, by means of a double pair of mortised blocks, 29, which are carried by the 20 horizontal rudder frame, 28, in a manner identical, with the blocks, 14, carried by the 25 main wing sticks 13.

To limit the passage of the rear ends, 25, of the fuselage sticks 18 and 19, thru the 30 mortised blocks, 29, a relatively wide U clip 30, is secured to the outer side face of the rear stick, 27, forming the horizontal rudder, 28, for the abutment of the fuselage ends 25, against the U clip 30, in a manner similar 35 to that employed at the front of the kite structure.

In order to secure the main wings 11 and 12, and the horizontal rudder, 28, on the front and rear ends of the fuselage sticks, 40 18 and 19, against lateral displacement, I employ a cord, 31, having one end thereof detachably secured by means of a suitable screw eye, to a point adjacent the upper end of the vertical strut, 23, and extending 45 to and connected to the front horizontal rudder stick, 27, by means of another screw eye centrally secured in the said stick, 27, between the rear end portions of the fuselage sticks, 18 and 19, and then returned to a 50 point adjacent the lower end of the strut, 23, and detachably secured thereto.

To the cord, 31, thus extended, inwardly of and parallel with the fuselage sticks, 18 and 19, a section of paper or fabric is suitably secured thereto and extended adjacent each of the secured ends thereof, to form a vertical wall between the said fuselage forming sticks, 18 and 19, adapted to balance the kite structure in conjunction with the vertical rudder, 32, hereinafter described.

The vertical rudder, 32, comprises a section of spring wire formed into a substantially semi-circular frame with its free ends, 33, bent to extend laterally therefrom.

65 The rudder, 32, is also covered with paper

or fabric, and with the free ends, 33, thereof pivotally and removably inserted in suitable holes drilled in the mortised blocks, 29, immediately above the rectangular apertures, 26, therein, by springing the wire frame of the rudder, 32, slightly together for inserting the ends, 33, thereof with the holes therefor in the blocks, 29.

In order to maintain the vertical rudder, 32, in a vertical position, a cord, 34, is secured thereto with the ends of the cord secured to the ends of the front horizontal rudder stick, 27.

The outer ends of the upper and lower wings, 11 and 12, are detachably held in alignment and connected by means of a pair of brace rods, 35, which are centrally pivoted one upon the other, as indicated at 35', and further provided with an opening in each end of the brace rods, 35, for passing 85 the extreme ends of the wing sticks, 13, therethru.

The said pivoted brace rods, 35, are held in a fixed position by means of a pair of horizontal stretch rods, 36, which are attached to the ends of the wing section, 11, in conjunction with the brace rods, 35, and provided with a suitable aperture in each end thereof, to be extended between and connected to the two upper ends of the sticks 13, forming the wing section 11, at each end thereof, to keep the upper and lower wing surfaces taut, as clearly shown in Fig. 1, of the drawing.

The said brace rods 35, are adapted to retain the stretch rods 36, which are in turn held in position on the ends of the sticks 13, forming the upper and lower wing sections 11, and 12, by means of the cords 37, having a suitable hook at each end thereof, and adapted to be attached to the ends of the brace rods 35, by means of the small apertures 37', therein, with the opposite end of the cords 37, likewise attached to the free ends of the inner stick 27, of the horizontal rudder 28, to prevent the flexing of the fuselage members 18, and 19, and to maintain the horizontal rudder 28, in parallel alignment with the wing sections 11, and 12.

To further provide for maintaining the equilibrium of the aeroplane kite when in flight, and to prevent the bending or flexing of the lower wing section 12, due to the downward pull of the control cord for the kite, thereon, I provide an additional pair of auxiliary wing surfaces 38, which comprise rectangular sections of paper or fabric, with suitable cords secured to the major length edges thereof, and with suitable hooks carried by the extended free ends of the cords 39, for securing the said wing surfaces 38, between the upper and lower wings 11, and 12, in a diagonal manner, with one end thereof hooked to the upper end por-

tions of the vertical struts 21, and 23, and with the opposite end of the wing surfaces 38, hooked to the lower free ends of the pivoted brace rods 35.

5 The diverging or angular position of the auxiliary wing surfaces 38 create tension on the centre of the upper wing 11 and on the outer end portions of the lower wing 12, and the tighter the auxiliary wing surfaces 10 38 are arranged the greater the tension on the upper and lower wings 11 and 12. It is possible to so increase the tension as to create a slight curvature in the upper and lower wings 11 and 12, thereby rendering the 15 kite more stable in its flight.

A suitable tie connection is made between the lower wing 12, and the auxiliary wing surfaces 38, adjacent the outer ends thereof, as indicated at 40, to prevent the auxiliary 20 wing surfaces, 38, from assuming an arcuate formation.

In order to give a realistic aeroplane appearance to the kite, and to further imitate the sound of a conventional type of heavier 25 than air flying machine, I provide a propeller, 41, which is centrally pivoted to and in front of the vertical strut, 21, and adapted to be rotated at a high rate of speed by the air current rushing into the 30 face of the kite when in flight.

The said propeller is further provided with an aperture, 42, in each blade adjacent the end thereof, and said apertures of a size required to create a whirring sound upon 35 the rotation of the propeller.

A bridle or control cord, 43, is further attached to the kite at several points, and consists of the main or controlling cord, 44, having one end thereof secured centrally 40 and to the under side of the mortised block, 29, carried by the under side of the inner stick, 27, forming the horizontal rudder, 28, by means of a suitable screw eye, and extends forwardly along the longitudinal center 45 of the kite, to a point substantially under the front edge of the lower wing, 12, where the cord, 44, is connected in the center of an auxiliary cord, 45, disposed at right angles to the main cord, 44, and connected 50 to the ends of the front stick, 13, forming the lower wing, 12, by means of a short section of cord, 46, approximately 4" long which is normally positioned and secured in a vertical manner between the main cord, 44, and the cord, 45, as clearly shown in the 55 drawing, the cord, 43, continuing from the joining point between the cord, 44 and 45, and provides the main control cord, 43.

The length of 4", required for the bridle 60 cord section, 46, has been determined by protracted experiments to be the correct length for maintaining the kite in flight in the manner set forth.

In order to create an accurate miniature 65 of approved aeroplane construction, I have

provided simple means for staggering the leading edge of the upper wing section, 11, slightly ahead of the leading edge of the lower wing section, 12, by means of a cord, 47, secured to and extended between a screw 70 eye carried by the upper portions of the rear vertical strut, 23, and a similar screw eye carried by the lower portion of the front vertical strut, 21.

The cord, 47, when so extended and secured, assumes an angle of approximately 45°, and in addition to staggering the wing sections, 11 and 12, upon tensioning the cord, 47, it also imparts an angle of incidence to the wing sections, 11 and 12, relative to the position of the fuselage.

From the foregoing, it will be readily apparent to those skilled in the art, that I have provided a novel, entertaining and highly interesting kite, of educational value 85 in teaching the young the art of aeronautics or sustained flight, and while I have shown and described one practical embodiment of my invention, it is to be observed that I do not limit myself to the exact details as set 90 forth, but consider myself at liberty to make such changes and modifications as fairly fall within the scope of the appended claims.

I claim:

1. In a knock-down aeroplane kite, the 95 combination of a fuselage frame and superposed plane sections including a horizontal and vertical rudder therefor, of means detachably connecting said frame, plane sections and horizontal rudder, auxiliary wing 100 surfaces positioned and secured between said plane sections, means for staggering said plane sections to impart an angle of incidence thereto relative to said fuselage frame and horizontal rudder, a control cord 105 having a multiple point suspension from said kite adapted to maintain true flight equilibrium, said auxiliary wing surfaces providing means for counteracting the pull of said cord on said plane sections and 110 maintaining the rigidity thereof.

2. In a knock-down aeroplane kite, the 115 combination of a fuselage frame and superposed plane sections including a horizontal and vertical rudder therefor, of means detachably connecting said frame, plane sections and horizontal rudder, auxiliary wing 120 surfaces positioned and secured between said plane sections, means for staggering said plane sections to impart an angle of incidence thereto relative to said fuselage frame and horizontal rudder, a control cord having a multiple point suspension from said kite adapted to maintain true flight equilibrium, said auxiliary wing surfaces providing means for counteracting the pull of said cord on said plane sections to maintain the rigidity thereof, a propeller pivoted 125

to said first named means and disposed centrally and forwardly of said plane sections, 130

and means provided in the blades of said propeller for creating a whirring sound upon the rotation thereof.

3. In a knock-down aeroplane kite, the combination of a collapsible fuselage frame, super-posed main plane sections including a horizontal and vertical rudder therefor, means carried by said plane sections and horizontal rudder for slidably receiving the front and rear ends of said fuselage frame in conjunction with the vertical struts for said plane sections, means connecting said plane sections and horizontal rudder for preventing lateral displacement thereof, auxiliary wing surfaces angularly disposed between the said plane sections and from the center to the opposite ends thereof, a propeller rotatably pivoted to one of said vertical struts and embodying means for producing a whirring sound upon the rotation thereof, brace members connecting the free ends of said plane sections, a plurality of cords having hooks and eyes associated therewith to provide rigging for the assembled kite, and a bridle control cord secured to said kite.

4. In a knock-down aeroplane kite, the combination of a collapsible fuselage frame, a pair of super-posed plane sections, vertical strut means for spacing and joining said plane sections, means carried by said plane sections for slidably receiving the spaced super-posed front ends of said fuselage frame, a horizontal rudder, means carried by said rudder for slidably receiving the joined rear ends of said fuselage frame, cord means connecting said plane sections and horizontal rudder against lateral displacement on said fuselage ends, a vertical rudder detachably carried by said horizontal rudder, means for maintaining said vertical rudder in a fixed position, and cord means connecting said vertical struts for staggering the upper plane section ahead of the lower plane section and to provide an angle of incidence to the main plane surface relative to said fuselage frame.

5. In a knock-down aeroplane kite, the combination of a collapsible fuselage frame, a pair of super-posed plane sections, vertical strut members spacing and joining said plane sections, mortised means provided in central alignment on the major edge surface of said plane sections for slidably receiving the spaced super-posed front ends of said fuselage frame with the simultaneous passage of said front ends through the apertured upper and lower ends of said strut members, stop clips carried by said plane sections and horizontal rudder therefor in alignment with said mortised means, hook, eyelet and cord means connecting said plane sections and horizontal rudder carried by the rear ends of said fuselage frame against lateral displacement, a vertical rudder

der detachably carried by said horizontal rudder, cord guy members connecting said vertical rudder, horizontal rudder and plane sections in adjusted relation, auxiliary plane surface members angularly disposed between said plane sections and extended from the center of the upper plane section to the lower outer ends of the lower plane section, and cord means connecting said strut members for staggering said main plane sections relative to said fuselage frame.

6. In a knock-down aeroplane kite, the combination of a pair of super-posed fuselage forming members, including super-posed main plane sections and horizontal and vertical rudders therefor, means carried by said plane sections and horizontal rudder for slidably fitment of the front and rear fuselage ends in said means jointly with the apertured ends of a pair of vertical struts disposed between and connecting said plane sections, a propeller pivoted to one of said struts, means associated with said propeller for effecting a whirring sound upon the rotation thereof, auxiliary wing surfaces angularly disposed between said main plane sections, flexible means secured to said vertical struts for staggering the said plane sections upon the tensioning thereof to impart an angle of incidence to said sections relative to said fuselage members, and cord means connecting said plane sections and horizontal rudder against lateral displacement on the front and rear ends of said fuselage members.

7. In a knock-down aeroplane kite, the combination of a fuselage frame and super-posed plane sections including a horizontal and vertical rudder therefor, of means detachably connecting said frame, plane sections and horizontal rudder, including vertical struts for spacing said plane sections, auxiliary wing surfaces angularly secured between said plane sections from the center to the opposite outer ends thereof, means for staggering said plane sections to impart an angle of incidence to the surface thereof relative to said fuselage frame and horizontal rudder, a control cord having a multiple point suspension from said kite adapted to maintain true flight equilibrium, said auxiliary wing surfaces providing means for counteracting the pull of said cord on said plane sections to maintain the rigidity thereof, a propeller pivoted to one of said struts and disposed centrally and forwardly of said plane sections, and means provided in the blades of said propeller adjacent their ends for creating a whirring sound upon the rotation thereof.

8. An aeroplane kite comprising a fuselage frame provided with a horizontal tail rudder and forward upper and lower wing surfaces, a control cord with a multiple point suspension from said kite to maintain true

flight equilibrium, and diverging auxiliary wing surfaces connected to the central portion of the upper wing surface and to the outer end portions of the lower wing surface, and exerting tension on said latter wing surfaces and resisting the pull on the control cord.

9. In an aeroplane kite, the combination with a fuselage frame provided with tail rudders, of super-posed wing surfaces at the forward end of the fuselage frame, and auxiliary wing surface connected to the centre of the upper wing surface and diverging downwardly and laterally and connected to the outer ends of the lower wing surface creating substantial tension on said wing surfaces and rendering the kite more stable in flight.

10. In an aeroplane kite, the combination with a fuselage frame provided with tail rudders, of super-posed wing surfaces at the forward end of the fuselage frame, and auxiliary wing surface connected to the centre of the upper wing surface and diverging downwardly and laterally and connected to the outer ends of the lower wing surface creating substantial tension on said wing surfaces and rendering the kite more stable in flight, and a control cord having a multiple point suspension from said kite to maintain true flight equilibrium and resist the tension exerted by the auxiliary wing surfaces.

11. In an aeroplane kite the combination with a fuselage frame comprising upper and lower members, of super-posed wing surfaces provided with operable detachable connections with the members of the fuselage frame, tail rudders provided with operable detachable connections with the upper and lower members of the fuselage frame, and

means interposed between the members of the fuselage frame and operatively and detachably connecting with certain of the members of the wing surfaces and certain of the members of the tail rudders, to retain the elements of the kite assembled.

12. In an aeroplane kite the combination with a fuselage frame comprising upper and lower members, of super-posed wing surfaces provided with operable detachable connections with the members of the fuselage frame, tail rudders provided with operable detachable connections with the upper and lower members of the fuselage frame, and means interposed between the members of the fuselage frame and operatively and detachably connecting with certain of the members of the wing surfaces and certain of the members of the tail rudders, to retain the elements of the kite assembled.

13. In an aeroplane kite, the combination with a fuselage frame provided with tail rudders, of super-posed wing surfaces at the forward end of the fuselage frame, and auxiliary wing surface connected to the centre of the upper wing surface and diverging downwardly and laterally and connected to the outer ends of the lower wing surface creating substantial tension on said wing surfaces and rendering the kite more stable in flight, and means connecting the edges of the auxiliary wing surfaces and those of the lower wing surface, thereby preventing the auxiliary wing surfaces from assuming arcuate formation.

In testimony whereof I affix my signature.
EDISON A. FOUNDS.
